DESIGN FOR A CONTAINER FOR PERFUME BOTTLES

Henry Worth and Samuel Tom Phillips,
New York, N. Y.

Application February 9, 1939, Serial No. 82,896

Term of patent 7 years

To all whom it may concern:

Be it known that we, Henry Worth and Samuel Tom Phillips, both citizens of the United States, and residents of the city, county, and State of New York, have invented a new, original, and ornamental Design for a Container for Perfume Bottles, of which the following is a specification, reference being had to the accompanying drawing, forming a part thereof, in which

Fig. 1 is a perspective view of a container for perfume bottles, showing our new design, and Fig. 2 is a perspective view of the container in open position. The opposite, or rear, side of the container is substantially the same as the front shown, except that the lock elements are omitted.

We claim:

The ornamental design for a container for perfume bottles, as shown.

HENRY WORTH.
S. TOM PHILLIPS.
